UNITED STATES PATENT OFFICE

2,630,250

MEASURING DISPENSER CONSTRUCTION

Robert W. Keiter, Toledo, Ohio

Application September 18, 1950, Serial No. 185,380

5 Claims. (Cl. 222—456)

1

This invention relates to containers, more particularly those fabricated from paper-board or the like, wherein a predetermined measured fractional quantity of its contents may be discharged therefrom by maneuvering the container through a cycle of positions.

An object of this invention is to provide a container having an interior construction which provides one or more measuring discharge troughs therein.

Another object of this invention is to provide an insert to be affixed within a container which not only provides a plurality of measuring discharge troughs or bins, but also forms a substantial reinforcement to the container as a whole.

Another object of this invention is to provide a sealed container having a plurality of measuring bins therein, wherein sections of the container walls are readily removable to form discharge ports for the bins.

And another object of this invention is to provide an insert for a container of the class indicated, so proportioned and positioned that the bins will discharge through their respective ports, a reasonably accurate predetermined quantity of the container housed material, with each manipulation designed for that purpose.

Other objects and advantages of this invention relating to the arrangement, operation and function of the related elements of the structure, to various details of construction, to combinations of parts and to economies of manufacture, will be apparent to those skilled in the art upon consideration of the following description and appended claims, reference being had to the accompanying drawings forming a part of this specification wherein like reference characters designate corresponding parts in the several views.

Referring to the drawings:

Fig. 1 is a perspective view of a container embodying the invention herein;

Fig. 2 is a view on the line II—II, Fig. 1;

Fig. 3 is a view on the line III—III, Fig. 2;

Fig. 4 is a plan view of a portion of the inner wall side of a container blank, having a form of the insert blank applied thereto;

Fig. 5 is a view similar to Fig. 4, showing a modified form of the insert blank positioned on the container blank;

Fig. 6 is a view similar to Fig. 2, embodying the modified insert blank of Fig. 5; and

Fig. 7 is a perspective view showing a container embodying the invention herein, the container being held in a contents discharging position.

2

The container proper may be any one of the various sizes commonly used to package powders or granular materials such as employed in great quantities for the retail distribution of detergents, soap powders, beads, etc. These usually, are of a rectangular cross-sectional shape and of a size to hold a bulk sufficient to provide several service portions. The housewife, for efficient use of the material, uses one size portion for a single dish-washing or small laundry operation, while a full laundry operation would require a larger portion. It is one purpose of this invention to provide a package which will dispense either size portion at will.

The container is formed by folding blank 10 according to the pattern provided by scoring 12. Herein, this provides a hexahedron with top 14, bottom 16, major side walls 18, 20, and minor or end walls 22, 24.

These walls define the four corners 26, 28, 30 and 32.

One form of the insert blank 34 is herein shown (Fig. 4), with scoring 36 providing a central major strip portion 38 and an integral minor strip portion 40, a major triangular section 42 continuing from the portion 38 and a minor triangular section 44 continuing from the minor portion 40. Terminal flaps 46, 48, provide continuations of the triangular sections 42, 44, respectively.

The blank 34 is attached to the inner wall forming side of the blank 10 by some suitable adhesive 50 so that the upper edges of the portions 38, 40, are spaced inwardly or below the top defining scoring 12. The adhesive may be selectively distributed but for economy and meeting most demands, it appears sufficient to stitch the portion 38 onto the major container side wall 20.

The superimposed blanks are folded and as the container is formed, the triangular sections 42 and 44 will form a pair of bins 52, 54, diagonally opposite and across the corners 26, 30. The inwardly positioning of the blank from the top provides a clearway 56 from the container interior into the bins or chutes.

The sections 42, 44, wedge into chute forming positions while their tabs 46, 48, abut against the container walls 24, 18, additionally holding the set-up in a locked assembly. This arrangement also provides a material strut reinforcement for the container walls and therefore a lighter weight stock may be employed in the container so that the extra cost of the insert is met by the savings in the cost of the container proper.

The container blank 10 is provided with additional scored lines 58 which define island areas 60 which register with the lowermost portions of the bins 52, 54, on the corners 26, 30, in container set up position. When it is desired to discharge package contents, these areas 60 may be readily pinched out from the container body, thus forming bin bottom discharge ports 62.

In use, the container is tipped toward either bin 52 or 54, according to the quantity of material to be discharged. The respective bin is charged by the material flowing thereto by way of the clearance 56 between the container top and top of the bin. In normal handling, substantially the same amount of material will enter the bin during each charging tilt of the container. Then as the container is righted into a position such as illustrated in Fig. 7, the material 64 will freely flow from the bin through the port 62.

Only the bin contained material can escape during any one cycle of measuring. A finger may be placed over the opening 62 if desired, while a bin is being loaded and until discharge is permitted.

Referring to Figs. 5 and 6, the terminal tabs 46, 48, may be expanded into strips 66, 68, which will completely or substantially encircle the inner walls of the container to increase the reinforcement factor. Sections 70, 72, may have modified perimeters from the sections 42, 44, and be provided with axial scored lines 74. This develops four-sided polygonal bins within the polygonal container.

The strut effect provided by the bin forming blank portions, together with the substantial areas nested and fixedly attached to the inner walls of the container, serve to provide a container of unusual stiffness, with crush resistance and protection against bulge, even when light weight board is used in the fabrication of the container bodies.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirements of the prior art.

What is claimed and is desired to be secured by United States Letters Patent:

1. A container of the class described including

a top and bottom, pairs of opposing side and end walls providing corners therebetween, an insert formed from a blank of sheet material cut and scored to nest in one corner in spaced relation from the top to extend in diverging directions from said corner toward the two adjacent corners which are diagonally disposed, said insert providing a side wall reinforcement and a bin at each of said diagonally disposed corners tapered downwardly from the top toward their respective corners, and said container corners having ports in registry with the lower portions of said bins.

5 10 15 20 25 30 35 40 45 50 55 60 65 70 75 80 85 90 95

2. The structure set forth in claim 1 wherein the bin forming portions of the insert blank have terminal extensions to cooperate in strut reinforcements for the side and end walls of the container.

3. The structure set forth in claim 1 wherein said insert blank is generally tapered from end to end to thereby provide a pair of diagonally disposed bins of different capacities.

4. The structure set forth in claim 1 wherein the bin forming portions of the blank have extensions which enables the blank to substantially encircle the container interior.

5. In combination, a container of the class described having a polygonal cross-section; an insert therefor embodying a blank of sheet material cut and scored to nest in a first corner of said container in spaced relation with the top of said container, said blank providing a major strip portion extending from said first corner along and against an inner wall of the container toward a second corner and providing a triangular section disposed in tapered strut relationship across said second corner to provide a bin with an extension therefrom engaging the container, said blank also providing a minor strip portion extending from said first corner away from said major strip along and against another inner wall of the container toward a third corner to provide a triangular section disposed in tapered strut relationship across said third corner to provide another bin also having an extension therefrom engaging said container, and said second and third corners having parts in registry with the lower portions of said bins.
